UNITED STATES PATENT OFFICE.

FREDERICK E. SMITH, OF LOS ANGELES, CALIFORNIA.

MILK-BOTTLE HOLDER.

No. 882,754.

Specification of Letters Patent.

Patented Oct. 6, 1906.

Application filed March 1, 1903. Serial No. 303,597.

To all whom it may concern:

Be it known that I, FREDERICK E. SMITH, a citizen of the United States, residing at Los Angeles, in the county of Los Angeles and State of California, have invented a new and useful Milk-Bottle Holder, of which the following is a specification.

The main object of this invention is to provide a device for receiving and holding milk-bottles to facilitate the delivery and collection of such bottles by the milkman.

The invention comprises a holder that is adapted to be secured to a suitable support—for example, a door, wall, stoop, or other part or adjunct of a house—and to receive and hold the milk-bottle in either upright or inverted position, the bottles being placed upright in the holder when full and inverted therein when empty.

The accompanying drawings illustrate the invention.

Figure 1 is a perspective of the device. Fig. 2 is a perspective view showing the application of the holder to a door-frame. Fig. 3 is a side elevation of the holder, showing the use of the same in supporting a bottle in upright position. Fig. 4 is a similar view showing the use of the holder when the bottle is in an inverted position.

The holder comprises an upright or vertical member, provided with stop means and with a plurality of loops extending therefrom above the stop means. The device is formed, preferably, of a single piece of wire bent successively to form the several loops or stop means and also bent to form a plurality of eyes or rings 2 2', whereby the device may be fastened to a suitable support. Thus the wire is shown as bent at one end to form an upper eye 2, and below the same it is bent to form a ring or loop 3, extending in substantially a horizontal plane from the main body or portion 1 of the device, the wire being continued from said loop downwardly to form a part of the main or vertical portion 1 of the device and being then bent to form another ring 3', extending from said body portion similarly to ring 3 and of substantially the same size as ring 3 and then downwardly to form another part of body 1 and then outwardly from the main body portion 1 to form an arm 4' and an intermediate ring 4, smaller than the rings 3 3', then back and down as a

part of the main body of the device and around to form the bottom eye 2', and then out to form an arm 5, having a loop 6 at its end considerably smaller than the loop or ring 4. This loop or ring 6 serves as a stop. The loop or ring 4 serves either as a stop or as a lateral support for the bottle, as hereinafter set forth, and the rings 3 3' serve only as lateral supports.

The device is applied or secured by means of nails driven through the eyes 2 2' to any suitable support—for example, a jamb or frame of a door (see Fig. 2) on the side of a porch, post, or wall, or elsewhere, as desired.

In using the device the milkman will deliver the bottles in upright position into the holder, the bottle passing down within the rings 3 3' and coming to rest on the smaller ring 4. In case of a large bottle it will rest squarely on said ring, or in case of a smaller bottle it may tip over so as to find a lateral support against the one or both of the upper rings; but in any case it will be held securely in approximately upright position. When the bottle has been emptied, it is placed in the holder in inverted position, (shown in Fig. 4,) and the neck of the bottle being smaller will in general pass through the stop-ring 4, so that its end will rest on an arm or stop 5 6. In this position the bottle will drain or will be kept free from entrance of dirt, litter, dust, or rain thereinto.

What I claim is—

A milk-bottle holder consisting of a wire bent to form a body portion, eyes at the upper and lower ends thereof, two rings of substantially equal diameter, extending one above the other from the body portion, an intermediate smaller ring extending from said body portion below the aforesaid ring, to engage the bottom of a bottle inserted in the larger rings and to receive and hold the neck of the bottle when inverted, and a stop-ring smaller than said intermediate ring and below the same to engage the mouth end of the inverted bottle.

In testimony whereof I have hereunto set my hand, at Los Angeles, California, this 17th day of February, 1906.

FREDERICK E. SMITH.

In presence of—

ARTHUR P. KNIGHT,
VERNA A. TALBERT.
